UNITED STATES PATENT OFFICE.

WILLIAM MEYER, OF CHICAGO, ILLINOIS.

CIRCUIT-TIMING DEVICE.

1,175,541.

Specification of Letters Patent. Patented Mar. 14, 1916.

Application filed February 15, 1915. Serial No. 3,214.

To all whom it may concern:

Be it known that I, WILLIAM MEYER, a citizen of the United States, residing at Chicago, in the county of Cook and State 5 of Illinois, have invented a certain new and useful Improvement in Circuit-Timing Devices, of which the following is a full, clear, concise, and exact description, reference being had to the accompanying drawings, 10 forming a part of this specification.

The present invention relates to a circuit-timing device and is especially adapted to control the time of the energization of an X-ray bulb, or the like, in order to limit 15 the time of exposure of a patient to the X-ray treatment.

The object of the present invention is to provide an improved timing-device for electrical circuits, or the like.

20 The accompanying drawing, which forms a part of this specification, illustrates diagrammatically an embodiment of my invention.

The apparatus illustrated in the figure 25 consists essentially of a switch 1 in the circuit of the primary of the X-ray device, an electro-magnet 2 controlling the switch 1, a time-controlled element 3 and a connection between the electro-magnet 2 and the 30 time-controlled element, and a controlling circuit 4, having an automatic switch 5 and a manual switch 6 for properly controlling the circuit, as will be described later.

The switch 1 comprises a cup 7, having 35 mercury in the bottom thereof, and a plunger 8, which is connected to the other side of the primary X-ray circuit. The plunger 8 is insulated from but mounted upon the core 9 of the solenoid 2 and is 40 adapted to be moved into engagement with the mercury in the bottom of the cup 7 when the solenoid 2 is energized.

The time-controlled element 3 includes a dash-pot 10 having a plunger 11 slidably 45 mounted therein. The plunger 11 bears a stem 12, which is provided with suitable graduations, as indicated in the drawing. A handle 13 is provided for raising this plunger to any desired position in order to 50 cause the graduations to register with the indicating brake. The indicating brake comprises a sliding bar 14 which engages in notches in the stem 12. The bar 14 is held against the stem 12 by the tension of the

spring 20 and is slidably mounted in the 55 posts 21 and 22.

In prior art devices it has been customary to have the first movement of the plunger 9 release the brake and start the operation of the timing element. But, inasmuch as 60 it is necessary to maintain a distance of at least $\frac{3}{8}$ of an inch between the plunger electrode 8 and the surface of the mercury in the cup 7, an appreciable time elapses after the automatic timing device starts to work 65 before the main circuit is closed. Where the time of exposure is to be as short as one-tenth of a second, this lost time forms a very appreciable percentage. In order to overcome this, I have provided a lost motion 70 decoupling which will consume an equal amount of time in causing release of the brake, so that the timing can be made with any desired degree of accuracy. To this purpose, the short arm of the lever 23, 75 which is pivoted at 15 and which connects the plunger 9 with the brake 14, plays in a slot or notch 24. The other end of the brake lever 23 is connected to the plunger 9 of the solenoid 2. A spring, not shown, 80 normally holds the plunger 9 in raised position. The stem 12 bears a projection 16, which, as shown in the drawing, consists of a collar surrounding the plunger, which collar engages a spring 17 forming a part 85 of the automatic switch 5.

When the parts are in the position shown in the drawing, the controlling circuit 4 connects the solenoid 2 with the automatic switch 5 through the battery and through 90 the normally open controlling switch 6. A switch 19 is provided for cutting out the automatic switch 5 if it is desired to close the primary circuit of the X-ray apparatus for any considerable length of time. When 95 the switch 19 is thrown upon its alternate contact the automatic switch 5 will be included in the circuit, and the automatic timing element 3 will then become operative to open the circuit of the X-ray primary at 100 the end of any predetermined interval of time.

The operation of the device is as follows: If it is desired to use the automatic timing control the switch 19 is placed upon the alternate current contact A. The stem 12 is then raised by means of the handle 13 until the desired graduation comes opposite the

end of the brake 14. This stem 12 may be graduated in any preferred manner. It is shown in the drawing as graduated in 0.2 of a second period. The stem 12 is held in 5 raised position by the brake 14 until the energization of the electro-magnet 2 occurs. When the switch 6 is closed the electro-magnet 2 is energized. The core 9 plunges the electrode 8 into the mercury cup 7 to 10 close the primary circuit of the X-ray device. At the same time the brake lever 23 throws off the brake 14 and releases the stem 12 and this stem is then free to drop. At the expiration of the predetermined time 15 the collar 16 will engage the spring 17 and disengage it from the stationary contact 18. The controlling circuit 4 is thereby broken and the plunger 9 of the solenoid 2 is raised, breaking the contact of the primary of the 20 X-ray device at the mercury cup 7. The dash-pot 10 is provided with a valve or vent, not shown in the drawing, the degree of opening of which may be controlled by rotating the cap 21, secured to the bottom of 25 the dashpot 10. When the graduation "1" shown in the drawing at the bottom of the dashpot 10 is brought opposite the zero position on the dashpot, the time required by the plunger to drop the full length of the 30 stroke of the dashpot is one second. If the setting of the cap 21 be shifted from this position, the time of dropping of the plunger 12 will be correspondingly lengthened or shortened. If it is desired to close the 35 X-ray circuit for a period longer than that covered by the dropping of the plunger, the switch 19 may be moved to the position shown in the drawing, in which the automatic switch 5 will be cut out of the controlling circuit, and the switch 6 will hold the controlling circuit, and thereby the main 40 circuit, closed as long as it is depressed.

It is to be noted that when the automatic switch 5 is in circuit the key 6 is depressed 45 until the circuit has been broken at the switch points 17-18 by means of the time element.

I have found in devices of the prior art where stationary or contact springs are employed instead of the mercury cup 7 and the plunger 8, that there will be a tendency for these contacts to bounce or vibrate and thus destroy exact timing of the closing of the circuit. By means of the plunger 8 and 55 the mercury cup 7 this is avoided, and slight movement of the plunger 8 after the same enters the surface of the mercury is immaterial.

I consider the provision of means to delay 60 the operation of the timing device until the instant that the contacts are changing the circuit conditions, to be broadly new.

It is obvious that the same principle of 65 operation may be involved in controlling a normally closed circuit as well as the open

circuit which I have described and illustrated. It is also to be understood that my invention contemplates the employment of suitable adjustments for the various elements.

The above-described mechanism embodies the principles of cheapness, simplicity and reliability, and, although various changes may be made which will be apparent to those skilled in the art, I desire that these 75 changes or modifications be considered as coming within the spirit and scope of my invention as defined by the appended claims.

What I claim as new and desire to secure by Letters Patent of the United States is: 80

1. In a device of the class described, a normally-open working circuit including a plunger and a mercury cup, an electro-magnet controlling said plunger, a control-circuit for said electro-magnet, contacts in said 85 control circuit, a timing element adapted to open said contacts to break said control circuit, a brake normally restraining the action of said timing element, a connection between said brake and said magnet, said connection having lost motion to cause the plunger and the cup to close the circuit simultaneously with the release of the brake, and a switch for closing said control circuit.

2. In a circuit-timing device, a working circuit having a pair of contacts, electro-magnetically controlled means for moving one of said contacts to change the condition of the circuit therethrough, a control circuit for said means, a manually operated switch for controlling said circuit, an automatic timing device for removing control of said means from said controlling circuit after a predetermined period of time, a connection between the electro-magnetic means and said timing means, said connection comprising means for delaying the starting of said timing device until the instant of change of circuit condition through said working circuit contacts. 100

3. A circuit-timing device comprising a normally open working circuit having a movable contact to close said circuit, an electro-magnet controlling said movable contact, a control circuit for said electro-magnet, contacts in said control circuit, a timing element adapted to open said contacts to break said control circuit, a brake connected to said magnet and adapted to be released thereby, said brake normally restraining the action of said timing element, the connection between said brake and said magnet having means to delay the release of said brake until the working circuit contacts are closing the working circuit, and a switch for closing said control circuit. 110

4. In combination, a pair of normally separated contacts, one of said contacts being movable, means for moving said movable contact into engagement with said other

- contact, and a timing element having means for determining and indicating the time during which said contacts are closed, said first means and said timing element having 50
 5 a loose coupling between them to allow the gap between said contacts to be closed at the instant that the timing device begins to operate.
5. In combination, a timing device, a 10 brake normally restraining the action of said timing device, a pair of normally separated contacts, one of said contacts being movable into engagement with said other contact, and common means for releasing 15 said brake and for moving said movable contact into engagement with the other contact, said common means and said brake having a loose coupling between them to allow movement of said movable contact prior to release 20 of said brake.
6. In combination a pair of normally separated contacts, one of said contacts being movable, means for moving said movable contact into engagement with said other contact, timing means governing said first 25 means, and a loose coupling between said contact moving means and said timing means governed by said first means to institute the operation of said timing element to 30 allow the gap between said contacts to be closed as the timing device begins to operate.
7. In combination a pair of normally separated contacts, one of said contacts being movable, a solenoid having a plunger for 35 moving said movable contact into engagement with said other contact, a timing device for shutting off the current in said solenoid, means connected to said plunger to start said timing device after the plunger 40 begins to move to allow the gap between said contacts to be closed before the timing device begins to operate.
8. In combination a pair of contacts, said contacts comprising a movable plunger of 45 resilient metal, and a stationary mass of non-resilient metal, an electro-magnet having a movable magnetic element for operating said plunger, a circuit for said electro-magnet, a timing device which operates af- ter a predetermined period of time to open 50 said circuit, a lever connected between said plunger and the timing device for starting said timing device.
9. In combination, a solenoid having a plunger, a cup, a conducting liquid in said 55 cup, said plunger and said liquid forming a pair of normally open contacts for a working circuit, a control circuit for said solenoid, a timing device which operates after a predetermined period of time to open said 60 control circuit, a brake for said timing device and a lever connected between said plunger and said brake to start the operation of the timing device.
10. In combination a solenoid having a 65 plunger, a contact mounted on said plunger, a mercury cup coöperating with said contact, a dashpot having a vertical stem, a horizontal slide having spring means to cause said slide to engage said stem, a bell 70 crank lever having one arm attached to said plunger and the other arm playing in a notch or slot in said slide, a circuit for said solenoid and contacts in said circuit controlled by said dashpot. 75
11. In a device of the class described, the combination of a working circuit having a pair of normally opened contacts, said contacts comprising a vertical plunger and a mercury cup below the same, an electromagnet having a movable magnetic element connected to said vertical plunger to operate the same, a control circuit for said electromagnet, a manual switch for said control circuit, an automatic time controlled element, a switch governed by said time controlled element, and a lever connected between said movable magnetic element and said time controlled element, to start the operation of said time controlled element. 80 85 90

In witness whereof, I hereunto subscribe my name this 11th day of February, A. D. 1915.
